UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-GEAR FOR PASSENGER EQUIPMENT.

1,302,072.

Specification of Letters Patent. Patented Apr. 29, 1919.

Application filed March 23, 1917. Serial No. 156,917.

To all whom it may concern:

Be it known that I, JOHN F. O'CONNOR, a citizen of the United States, residing at Chicago, in the county of Cook and State of Illinois, have invented a certain new and useful Improvement in Draft-Gears for Passenger Equipment, of which the following is a full, clear, concise, and exact description, reference being had to the accompanying 10 drawings, forming a part of this specification.

This invention relates to improvements in draft gears for passenger equipment.

One object of the invention is to provide 15 a draft gear more particularly adapted for passenger cars wherein the arrangement is such that a high capacity frictional resistance is obtained in buff and a spring resistance only in draft.

Another, and more specific object of the 20 invention is to provide a draft gear wherein is obtained a greater movement in buffing than in draft.

In the drawing forming a part of this 25 specification, Figure 1 is a longitudinal vertical sectional view of a draft rigging showing my improvements in connection therewith. Fig. 2 is a horizontal sectional view taken on the line 2—2 of Fig. 1 and illustrating the position assumed under full buff. Fig. 3 and 4 are vertical transverse sectional views taken on the lines 3—3 and 4—4 of Fig. 1, respectively.

In said drawing 10—10 denote channel-shaped center or draft sills of a car under-frame, to the inner faces of which are secured stop castings 11—11 having front stops 12 and rear stops 13. Mounted between the sills and coöperating with the stop 30 members is my improved gear, hereinafter described, the gear being connected to the draw bar 14 by a yoke 15, the yoke and draw bar having a pivotal connection, as indicated at 16, and as customary in passenger car 35 equipment. All the parts are supported by a detachable saddle plate 17. The improved gear, as shown, comprises a casting A having a friction shell portion 18, a spring casing 19 telescoped within the casting A, friction 40 elements coöperable with the friction shell, and hereinafter described, a front spring 20, a rear spring 21, and transversely extending keys 22—22. The casting A is held rigid or immovable with respect to the stops 45 by means of front and rear laterally extend-

ed shoulders 23—23 that engage the front and rear stops. The friction elements coöperable with the shell 18 may be of any suitable design and, as shown, comprise friction shoes 24, wedge 25 and anti-friction 50 rollers 26 interposed therebetween. The front spring 20, which consists of an outer and an inner coil, bears at its front end against the friction shoes to resist their inward movement with respect to the shell in a well known manner. Said spring 20 at its rear end bears against the transversely extending keys 22 and the latter are movable in corresponding slots 27—27 provided in the side walls of the casting A near its rear 70 end. The normal position of said keys 22 is at the forward ends of said slots 27 and as illustrated in Fig. 1. The rear spring 21 bears at its front end against the keys 22 and at its rear end against the back wall of the 75 spring casing 19. The casting A and the casing 19 are provided with coöperable engaging annular shoulders 28 to limit the outward movement of the casing relatively to the casting A. A retainer bolt 29 extends 80 through the wedge 25, between the shoes, through the spring 20, and between the keys 22, said bolt having an enlarged washer 30 at its rear end which bears against the rear faces of the keys 22 to thereby limit the forward movement of the retainer bolt.

The operation is as follows: In buffing, the draw bar will bear against the wedge 25 and thereby force it and the friction shoes inwardly against the combined resistance of 90 the springs 20 and 21, it being apparent that the keys 22 float during this movement until said keys 22 engage the rear set of shoulders 23 provided on the casting A, which is held stationary. 95

During this operation, it is apparent that the rear spring 21 is held at its rear end by the casing 19 which is immovable since it is engaged with the casting A. By this arrangement, the draw bar is permitted as 100 much movement as may be desired, and usually three inches. In draft, inasmuch as the keys 22 are normally at the front ends of the slots 27 and the casting A is held immovable, it is apparent that the yoke will 105 only actuate the casing 19 and thereby compress the rear spring 21 only against said keys 22. During the draft action, the friction elements and front spring 20 remain inactive. The draft movement is limited by 110

the yoke engaging the rear end of the casting A, which amount of movement is preferably made less than the amount of buffing movement, ordinarily about one and one-half inches. To permit the casing 19 to move forwardly with respect to the casting A, the side walls of said casing are slotted, as indicated at 31, to slide over the keys 22. With the gear described, I obtain an easy 10 spring action under draft, thus facilitating the starting of trains while at the same time a sufficiently high frictional capacity is provided for all buffing movements.

I claim:

15 1. In a draft rigging, the combination with a friction shell having friction elements coöperable therewith, of two aligned springs adapted to simultaneously resist movement of the friction elements relatively 20 to the shell in one direction, and key means passing through said shell and interposed between the adjacent ends of the springs arranged to prevent transmission of pressure applied to the spring farthest from the 25 friction elements to the other spring when the gear is operated in the opposite direction.

2. In a draft rigging, the combination with a stationary friction shell and a spring 30 casing telescoped therewith, of friction elements coöperable with the shell, a spring within said shell, a spring within said casing, and means preventing outward movement 35 from normal position of the casing relatively to the shell but permitting inward movement relatively thereto.

3. In a draft rigging, the combination with draft sills and a friction shell immovably mounted therein, of friction elements coöperable with said shell at its forward end, 40 a spring at the rear of said elements, a second spring at the rear of the first named spring, both springs being within said shell, acting simultaneously throughout the entire stroke to resist inward movement of the 45 friction elements under buff, a draw bar, means connected to the draw bar for applying pressure to the rear end of the second named spring under draft, and means for holding the front end of said second named 50 spring stationary under draft, said means extending within the shell.

4. In a draft rigging, the combination with draft sills and a friction shell held in fixed relation therewith, of a spring casing 55 telescoped within said shell at its rear end, coöperating means on the casing and shell to limit the outward movement of the casing, transversely extending key means extending through the shell and casing, friction elements coöperable with the friction shell at its front end, a spring interposed between said elements and said key means, and a spring interposed between said key means and the rear end of said casing, said key 60 means being movable under buff and held stationary under draft.

In witness that I claim the foregoing I have hereunto subscribed my name this 7th day of March 1917.

JOHN F. O'CONNOR.
